UNITED STATES PATENT OFFICE.

FRANK W. SHUELL AND ELMER E. LEDBETTER, OF DETROIT, MICHIGAN, ASSIGNEES
TO THE EVER HOT HEATER COMPANY, OF DETROIT, MICHIGAN, A CORPORATION
OF MICHIGAN.

INTERNAL-COMBUSTION RADIATOR UNIT.

Application filed April 11, 1927. Serial No. 182,845.

The invention relates to heating systems of the type disclosed by Patent No. 1,594,074 issued to Frank Shuell and Elmer E. Ledbetter July 27, 1926, in which a series of internal combustion radiator units are arranged in the rooms of the dwelling and are thermostatically operated to maintain the desired temperature. In such systems the various radiator units are supplied with fluid fuel, preferably gas, and the products of combustion are forcibly withdrawn from the combustion chamber by a suction fan or equivalent means.

The object of the present invention is to obtain an improvement in the construction of the radiator units whereby a more efficient apparatus is secured and the cost of manufacture is considerably reduced. To this end we have provided the novel construction hereinafter described and illustrated in the drawings, wherein

Figure 1 represents a portion of the heating system with one of the radiator units shown in side elevation;

Figure 2 is a transverse section through the radiator unit on the line 2—2 of Figure 3;

Figure 3 is a longitudinal section through the radiator unit on line 3—3 of Figure 2 showing one of the cast sections from which the unit is constructed;

Figure 4 is a horizontal section on the line 4—4 of Figure 3.

Referring now more specifically to the particular construction of the apparatus as illustrated in the drawings, 10 indicates the radiator unit generally, 11 the fuel supply line, 12 the exhaust conduit and 13 the fan or blower for creating a suction in the exhaust conduit. The unit 10 comprises an outer casing 14 suitably supported by legs 15 and adapted to rest upon the floor. The casing is open at both the lower and the upper ends to permit the air in the room to circulate within the same and contact with the combustion chamber unit 16, which is arranged within the casing. As shown, the casing 10 is closed at the top and has the opening 17 for the heated air arranged in the upper part of the front wall so that the heated air escapes laterally into the room.

The combustion chamber 16 is of novel construction and is built up of two similar castings 18 and 19, each of which has a side wall

20 from which project the top marginal flanges 21. Each casting is provided with a series of horizontally extending baffles 22 formed integral with the side walls 20 and of the same width as the marginal flanges 21. The alternate baffles terminate short of the side marginal flanges 21, forming in effect the return-bent passageways 23. The main wall 20 of each casting is also provided with a series of vertically extending flanges or fins 24 projecting from the wall on the opposite side of the marginal flanges and baffles. The two similarly constructed castings are assembled together with the respective marginal flanges and the baffles abutting and are suitably secured together by bolts 25. Preferably the bolts extend at the four corners of the castings and pass through the apertured ears 26 provided therefor. For further securing the parts together intermediate bolts may be provided, and as shown, each casting has a centrally drilled aperture 27 extending through one of the intermediate baffles and has a boss 28 on the wall 20 in alignment therewith. When thus assembled the two castings form a continuous passageway 29 extending from the top to the bottom of the combustion chamber and forming a flue for the combustion gases.

The combustible charge is preferably introduced into the upper passageway of the combustion chamber and for this purpose the casing has an aperture 30 in the end wall through which is inserted a gas burner 31, or other suitable fuel-supplying means. The gas burner is preferably of the modified Bunsen burner type so constructed as to be capable of operating under varying conditions of gas pressure from a tiny pilot light to a strong flame. The desired quantity of air is introduced into the combustion chamber through the aperture 32, which may either be calibrated to obtain the desired proportion or provided with suitable regulating means.

The exhaust conduit 12 connects into the combustion chamber in the lower horizontal passageway thereof and by reason of the suction from the blower 13, a forced draft is created in the combustion chamber, causing the combustion gases to travel through the zigzag flue 29, during which travel the heat of combustion is dissipated through the walls

- of the combustion chamber and the vertical fins 24 to the air circulating within the outer casing 10. It is preferable to provide means for introducing auxiliary air into the exhaust products prior to their withdrawal through the exhaust conduit 12 in order to prevent condensation within the exhaust pipe because of the lowered temperature of the products. This auxiliary air is introduced 5 in the present instance through port 33 in the lower passageway of the combustion chamber, the amount being determined either by the calibration of the port or by regulating through the damper 34.
- 10 The operation of the system is similar to that described in the prior patent above referred to and by properly proportioning the amount of gas and air initially introduced into the combustion chamber and the amount introduced through the ports 33, a heating apparatus may be obtained having a very high heating efficiency; that is, the combustion may be rendered very complete and the temperature of the exhaust products kept very low.
- 15 Furthermore, by the proper regulation of the amount of air introduced, condensation within the unit and within the exhaust conduit may be entirely avoided without impairing the efficiency of operation.
- 20 For rendering the system automatic in operation a suitable thermostat 35 is arranged in the gas supply conduit 11 and shielded from the direct radiation from the unit by a protecting baffle 36.
- 25 For protecting the upper portion of the casing 14 from overheating due to the high temperature within the upper portion of the combustion chamber 16, baffles 37 are arranged at the sides of the combustion chamber in spaced relation thereto, thus shielding the casing from direct radiation.
- 30 It will be noted in Figure 3 that the intermediate baffles 22 are vertically spaced from each other by varying distances, which progressively decrease in amount from the upper portion of the combustion chamber to the lower portion thereof. The object of this arrangement is to provide sufficient cross sectional area in the horizontal passageways to adequately care for the products of combustion in the varying degrees of expansion and at the same time to provide for the maximum distance of travel while the products are confined within the combustion chamber unit.
- 35 Thus the upper baffle 22 is spaced sufficiently from the top of the combustion chamber to provide the desired cross sectional area for the initial combustion. As the heat is abstracted from the combustion products the gases are contracted in volume and less area is required to maintain a constant rate of flow and the baffles are therefore arranged closer together in the lower portions of the unit. The closer spacing of the baffles permits a greater number to be inserted in a combustion chamber of

given dimensions and therefore the effective length of the flue passageway is materially increased, resulting in a more efficient abstraction of the heat from the combustion products.

70

The air introduced into the combustion chamber is preferably derived from within the outer casing 14 and in the preferred construction both the main inlet aperture 32 and the auxiliary air port 33 are connected to a vertical conduit 38. This conduit is preferably constructed so that it may be entirely closed off from communication with the outside air by means of an automatically operable mechanism described in the copending application of Elmer E. Ledbetter filed on April 11, 1927, Serial No. 182,846. In general this construction comprises a pair of spring closed valves 39 and 40 arranged in the ends of the conduit 38 and normally maintained open by a connecting bar 41 and fusible link 42, the latter being arranged in the vicinity of the air inlet aperture 32. The connecting bar also has connected thereto a spring closed gas valve 43 for controlling the fuel supply to the burner 31. With this arrangement the air supply to the combustion chamber is drawn from within the casing 14 by the valves 39 and 40 and forcibly drawn through the combustion chamber by the suction fan. If for any reason the suction on the combustion chamber is reduced below a predetermined value through failure of the fan or some other defect in operation, the flame from the burner instead of passing through the combustion chamber will tend to pass outwardly by the upper valve 39, but this immediately fuses the link 42 and automatically closes the air valves 39 and 40 and the gas valve 43.

75

What we claim as our invention is:

90

1. A heating apparatus of the internal combustion type comprising a combustion chamber having an air inlet at the top thereof and an elongated flue passageway extending downwardly therefrom, means for introducing fuel into the upper portion of said combustion chamber adjacent said air inlet, and means for forcibly withdrawing the products of combustion from the lower portion of said combustion chamber.

100

2. A heating apparatus of the internal combustion radiator type comprising a closed combustion chamber having gas and air inlets in the upper portion thereof and an exhaust outlet at the bottom portion thereof, means for creating a suction at the exhaust outlet for withdrawing the products of combustion through the combustion chamber, and means arranged within said combustion chamber for compelling said products to travel through a circuitous path through the combustion chamber whereby the heat of combustion may be dissipated by radiation prior to the withdrawal of the exhaust products.

110

3. A heating apparatus comprising a cas-

130

ing having a series of vertically spaced horizontally extending baffles forming a series of horizontal passageways, said passageways being connected together at the opposite ends 5 to form a single flue conduit extending from the top to the bottom of said casing, a gas burner arranged in the uppermost passageway, an air inlet in said upper passageway, an exhaust conduit connected to the lower 10 passageway, means for producing suction in said exhaust conduit, an outer shell surrounding said casting open at the bottom and the top to permit circulation of air therethrough in contact with said casing, and a series of 15 vertically extending fins on the outer surface of said casing.

4. A heating apparatus comprising an outer shell, a combustion chamber within said shell having therein a series of horizontally 20 extending chambers, the ends of which are alternately connected together forming a single continuous passageway, means for introducing air and fuel into the upper chamber, means for creating a suction in the 25 lower chamber to draw the gaseous products through said passageway from the top to the bottom thereof, and a series of vertical fins projecting from said combustion chamber into the space enclosed by said outer shell. 30

5. A combustion chamber unit for an internal combustion heating apparatus comprising a pair of complementary castings, each having a side wall and transversely extending marginal flanges and having a series 35 of substantially parallel intermediate flanges, one end of each intermediate flange terminating at a point spaced from the marginal flanges, and means for securing said complementary castings together with corresponding flanges abutting.

6. A combustion chamber unit for an internal combustion heating apparatus comprising a pair of complementary castings, each having a side wall and transversely extending marginal flanges, each casting also 45 having a series of substantially parallel intermediate flanges integral with the casting and of the same height as said marginal flanges, each side wall having integrally formed therewith on the opposite side from intermediate flanges, a series of transversely extending fins, and means for securing said complementary castings together with the corresponding intermediate flanges abutting.

55 7. A heating apparatus comprising an outer shell, a combustion chamber within said shell having therein a series of horizontally extending chambers, the ends of which are alternately connected together forming 60 a single continuous flue passageway, said horizontally extending chambers being of

progressively diminishing cross sectional area from the upper to the lower portions of the combustion chamber, means for introducing air and fuel into the upper chamber, and means for forcibly drawing the gaseous products of combustion through said continuous passageway. 65

8. In a heating apparatus of the internal combustion radiator type, a closed combustion chamber provided with a series of substantially parallel baffles therein forming passageways alternately connected together at opposite ends, the baffles at the outlet end of 70 said combustion chamber being spaced closer than the baffles at the inlet end thereof, thereby increasing the distance of travel of the products of combustion. 75

9. In a heating apparatus of the internal combustion radiator type, an outer casing 80 having openings therein for the upward circulation of air, a closed combustion chamber within said outer casing having radiating projections on the outer surfaces thereof, means for introducing fuel and air into the upper portion of said combustion chamber, means for forcibly withdrawing the products of combustion from the lower portion of said chamber, and a series of substantially horizontal baffles within said combustion chamber 85 forming a series of parallel flue passageways connected in series, said baffles being spaced apart at progressively smaller distances from the upper to the lower portion of the combustion chamber, thereby increasing the 90 length of travel of the combustion products. 95

10. In a heating apparatus of the internal combustion radiator type, an outer casing having openings therein for the upward circulation of air, a closed combustion chamber 100 within said outer casing having radiating projections on the outer surfaces thereof, means for introducing fuel and air into the upper portion of said combustion chamber, means for forcibly drawing the products of 105 combustion through said chamber, and a series of substantially horizontal baffles within said combustion chamber forming a circuitous passageway for the products of combustion, said baffles in the upper portion of the 110 combustion chamber being spaced apart sufficiently to provide for the expanded products of combustion and the lower baffles being spaced progressively closer together toward the lower portion of the combustion chamber to increase the distance of travel of the 115 combustion products.

In testimony whereof we affix our signatures.
